MACHINE FOR MAKING COILED-COILS

Sten Wadsten, Bloomfield, N. J., assignor to
Westinghouse Lamp Company, a corporation of
Pennsylvania

Application October 27, 1933, Serial No. 695,379

36 Claims. (Cl. 153—64)

This invention relates to a machine for making coiled-coils and relates more particularly to a machine for practicing the method set forth in Patent No. 2,013,432 to R. H. Beebe issued September 3, 1935, for Method of making coiled coils and assigned to the same assignee as the present invention.

Although the present machine may be employed to produce coiled-coils of various sizes it is especially adapted to produce filaments for electric incandescent lamps.

As pointed out in the above mentioned patent, lamp filaments of the coiled-coil type are usually made by first forming a wire into a helical coil either by winding on a mandrel and dissolving out the mandrel or on a mandrelless coil-winding machine. This coil is then removed by immersing the coil in an acid bath, inert with respect to the coil but which dissolves the mandrel. This required a laborious and costly operation and the method set forth in the above mentioned patent provides a method whereby a coiled-coil may be produced by moving a member to progressively engage the turns of a primary coil to cause it to form a secondary coil. The method is preferably practiced in connection with a mandrelless coil-winding machine such as shown in Patent No. 1,670,499 issued May 22, 1928. The machine of this patent forms a coil without the use of a mandrel and serves to produce a primary coil which is fed to mechanism which operates upon the coil to form it into a secondary coil.

Although the present mechanism may be employed to either operate upon a helically coiled filament as it issues from a mandrelless coil-winding machine, it may also be employed to operate upon an indefinite length of helically coiled wire which has previously been made on a machine which employs a mandrel. In this case the mandrel may be removed in the usual manner and the coiled wire may be wound on a spool and fed to the present mechanism to form a secondary coil.

The selected embodiment of the invention, however, includes mechanism for making a secondary coil in conjunction with a mandrelless coil-winding machine as shown and described in the above last mentioned patent.

It is an object of the present invention, therefore, to provide a simple and effective arrangement of machine elements capable of diverting a primary helical coil into a secondary helical coil.

Another object of the invention is to provide means operating in conjunction with a coil-wind-

ing machine to divert the coil produced into a secondary coil.

Another object of the invention is to provide mechanism whereby a helical coil wound on a mandrelless machine may be moved through a predetermined path adjacent to mechanism operating to progressively engage the successive turns of the coil to form the same into a secondary coil.

Other objects and advantages of the invention will be understood from the accompanying drawings in which

Fig. 1 is a side elevational view of a mandrelless coil-winding machine including mechanism for shaping a primary coil into a secondary coil; 15

Fig. 2 is a plan view of the machine shown in Fig. 1;

Fig. 3 is a view taken on line III—III in Fig. 2;

Fig. 4 is a view looking in the direction indicated by arrows IV—IV in Fig. 2;

Fig. 5 is an enlarged detail view of mechanism for operating upon a primary coil to form the same into a secondary coil; 20

Fig. 6 is a cross sectional view of the mechanism shown in Fig. 5 showing mechanism for holding the secondary coil in position to enter a guide passage; 25

Fig. 7 is an enlarged diagrammatic view indicating the primary coil as it issues from the die and formed into a secondary coil;

Fig. 8 is a view taken on line VIII—VIII in Fig. 7; and

Fig. 9 shows a lamp mount with a coiled coil filament secured to the lead wires or conductors thereof. 30

As above set forth, the present invention is particularly adapted for forming a secondary coil from a primary coil made on a mandrelless coil-winding machine. A coil-winding machine of this type is shown in the drawing and comprises a suitable bed plate 10 for coil-winding mechanism indicated as a whole by the numeral

11 and a base 12 for reduction gearing 13. The reduction gearing is actuated by a motor 14 provided with a pulley 15 and a belt 16 which transmits motion to a pulley 17 at one end of a shaft

18 journaled in a bearing bracket 19. The shaft 18 is connected to one end of an extension shaft 21 by a universal coupling 22. The other end of this shaft is connected to one end of a stub

shaft 23 by means of a universal coupling 24. The other end of the shaft 23 is secured to gear segment 51 constituting part of mechanism, to be later described, for diverting a primary coil

into a secondary coil. 35

40

45

50

55

55

The mechanism 11 for forming the primary coil includes a disk 26 on the shaft 18. This disk is provided with a single tooth disposed to engage teeth of a gear wheel 27 on a shaft 28. The 5 segment 29 is mounted on an arm 31 one end of which is pivoted at 32 (see Fig. 3). The opposite end of the arm is provided with a set screw 33' which seats on a stop 34'. Thus the position of the toothed disk 26 may be adjusted with 10 respect to the pitch line of the teeth on the gear wheel 27. By this means a fine regulation may be obtained with respect to the relative movements of disk 26 and the gear wheel 27. As will be later understood, the tooth on the disk 15 26 causes a given movement of the gear wheel 27 which movement must be so governed that other mechanism will be regulated accordingly. Owing to the extremely small dimensions of the 20 primary coil being formed the degree of movement of the operative parts is extremely small and, although the amount of adjustment attained by slightly moving the disk 26 is small, it is in fact relatively great in so far as the present operations are concerned.

The disk 26 causes a movement of the gear wheel 27 which is mounted on the stub shaft 28 thus transmitting motion to the reduction gearing 29. The reduction gearing is arranged to drive a pair of shafts 36 and 37, which drive what 30 are termed force rollers 38 and 38' respectively. These rollers are so disposed as to grip a wire 41 between the surfaces of their peripheries and drive the wire into a cavity die 42. This die and the mechanism for holding it in position 35 to receive the wire is indicated as a whole by the reference numeral 33 and includes various adjustment devices for angular, lateral and vertical adjustment of the die which adjustment mechanism is clearly described in the above mentioned Patent No. 1,670,499 covering the 40 mandrelless coil-winding machine.

This patent also clearly shows the die and the manner in which the wire issues in the form of a helical coil which in the present drawing is indicated by the numeral 34 (see Fig. 6). The wire 41 for making the primary coil may be led from a spool 41' over a drum 42', in a bight and thence to the force rollers 38 and 38'. The drum 42' serves to actuate mechanism for cutting the coiled-coil into sections containing uniform 50 lengths of wire.

The coil 34, which is the primary coil in the present instance, is lead through a guide passage 35' formed in a sleeve 36' which sleeve constitutes a spindle for a pinion 37', the spindle being journaled in an adjustable standard or bracket 37''. The pinion 36 is in mesh with a similar pinion 39 rotatable on a stud 41' secured in the bracket 37'' which is provided with a foot piece 42'' slidable in a guide support 43. For the purpose of moving the bracket 37'' to adjust it in a horizontal plane the foot piece 42'' is provided with a threaded aperture 44 to receive a screw 45 the free end of which is provided with a head 46 which abuts against a plate 47 so that a rotation of the head 46, which causes a rotation of the screw, will serve to move the bracket 37''. When the helically wound filament or primary coil 34 travels through the passage 35' it rotates at relatively high speed about the longitudinal axis of the helix, this rotation being caused by the mandrelless operation of coiling. For the purpose of winding the primary coil into a secondary coil 50 the sleeve 36' is provided with 70 a nose piece 48 and it is at this point that the

operation of forming the secondary coil is performed.

As set forth in the method disclosed in the above mentioned Patent No. 2,013,432, it has been found that, if the turns of a helically wound 5 coil of a given pitch are spread apart at predetermined points on the circumference of the coil, the helically wound coil will take the form of another helix. The present construction shows mechanism operating on a primary coil to move 10 a member or spreader between successive turns of a primary coil.

When operating upon a helically wound coil, as it issues from a coil-winding machine and is thus rotating, it is necessary to provide means 15 so coordinated and timed as to perform the spreading operation after each revolution of the primary coil so that the point at which the spreading takes place is always the same with respect to the circumference of the primary coil. 20

It has been found practical to perform the spreading operation by means of a knife-like member 49 which may be carried on a holder 51 of disk 25. The disk is rotatable on the shaft 23 driven by the motor 14. The disk 25 is provided with a toothed segment 52 disposed in mesh with the pinion 39. The segment and pinion 39 are so proportioned and arranged that a movement of the segment will cause one complete rotation of this pinion. This will, obviously, cause 30 a complete rotation of the pinion 37' and sleeve 36' which is rotatable therewith.

Extending from the nose piece 48 of the sleeve is a guide finger or stub guide 53 and, as the coil 34 issues from the sleeve it passes adjacent 35 to and travels over an abutting surface 54 (see Fig. 8) on the guide 53. At this point the separator member or blade 49 is moved between the turns of the coil 34.

The blade 49, carried by the disk 25, is so timed 40 in its operation that with each complete rotation of the primary coil about its axis the blade enters between two adjacent turns. This operation is progressive and as each successive turn advances, the blade passes between it and the next 45 succeeding turn. With the arrangement shown the points of separation for the turns will be in a straight line along the length of the primary coil since the blade 49 is timed to perform its spreading operation after each complete rotation of the primary coil about its longitudinal 50 axis.

As the blade operates to separate the turns, the primary coil begins to form the secondary coil 50 which winds itself about and is carried by the 55 guide or finger 53. This holds the secondary coil to form and prevents distortion due to any whipping action that may occur since, as above explained, the primary and consequently the secondary coil will rotate. As the secondary coil 60 leaves the guide finger it moves through a guide tube 55 and across a blade 60 which, in conjunction with the edge 60' of the tube 55 serves to sever the coil. Means for cutting the secondary coil into sections will be later described. 65

The guide finger 53 is, as above described, carried on the sleeve 36' and, therefore, rotates with the primary coil so that the secondary coil as it is made, will move with the primary coil and be held under control and fed into the guide tube 55. 70

With the present construction the primary coil winding operation is terminated when the blade 49 moves between the turns of the primary coil.

As above pointed out, the present machine is 75

so constructed that with each engagement of the blade 49 and the primary coil a termination of the coil-winding operation is effected. This is accomplished by means of the single toothed disk 26 which causes a rotary movement of the gear wheel 27. The shaft 21 which, as above described, is adjustably coupled to shaft 18, driven by pulley 17, and shaft 23 which carries the disk 25, translates motion to the holder 51 driving it continuously. By reason of the segment 52, however, the pinion 37 which carries the sleeve 36' is only rotated one complete revolution for each revolution of the disk. The rate of rotation of the sleeve is in timed relation to the rotation of the primary coil 34 about its longitudinal axis.

Owing to the relative movement between the single tooth disk 26 and the gear-wheel 27, only one complete coil winding operation is performed for each complete rotation of the disk 25 and the segment 52 thus rotates the sleeve 36' with the coil, and the blade 49 moves between adjacent turns of the wire at the end of the rotary movement of the primary coil or after each coil-winding operation. Thus, with the present mechanism, when the turns of the coil are separated, the coil-winding operation has stopped temporarily. The operation of making the primary coil may, however, be made continuous by providing a plurality of the blades 49 operating in timed relation to the rate of rectilinear movement of the primary coil.

It will be appreciated that the operation of the blade 49 must be timed accurately and in the present construction the disk 25 is, therefore, adjustable to move the segment 52 toward or away from the pinion 39 thus changing the pitch diameter and varying the degree of movement of the pinions and consequently the guide finger 53 on the nose piece 48.

Means for adjustably supporting the disk 25 may comprise an arm 50' having one end pivoted at 51'. The other end provides a bearing 52' for the shaft 23. Laterally projecting from the bearing and integral therewith is a short arm 53' pivotally connected with one end of an adjustor rod 54'. The rod 54' extends through and threadedly engages an aperture in an upright 55' and a hand wheel 56' is provided to draw the rod 54' to adjust the portion of the disk relative to the pinion 39. A lock nut 57' makes it possible to secure the rod in an adjusted position. The nose piece 36' is also slightly adjustable and is held against relative movement by a set screw 58 extending through a slot 57 on a flange on the sleeve 36'. The sleeve, and consequently the arbor, is thus adjustable with respect to the path of movement of the blade 49 and by such adjustments the pitch of the secondary coil may be varied.

As the secondary coil issues from the guide 55 it is severed into sections of uniform lengths. The machines for performing the severing operation include the knife 60 in conjunction with the end 60' which serves as a bed knife. This cutter or knife 60 is mounted on a plunger 65 reciprocal vertically in a guide plate 66. The lower end 67 of the plunger is disposed in contact with a set screw 68 at one end 69 of a lever member 71 balanced in a bearing 72.

The opposite end 73 of the lever is provided with a latch 74. This latch consists of a rocker member 75 pivoted at 76 and has an arm 77 normally held against a stop 78 by a spring 79; thus an engagement with one side of an arm 81 of the rocker member 75 will serve to depress the arm 73

by reason of the stop 78 and rock the lever 71 while an engagement of the opposite end 81 of the member 75 will permit the said member to move without actuating the lever 71.

It will, therefore, be evident that by engaging the rocker arm 75 the lever 71 may be actuated to lift the plunger 65 and cause the knife 60 to move across the bed knife 60' to sever the secondary coil. A spring 82 and a collar 83 on the plunger operate to normally return the plunger to its lowered position. It will be appreciated that the present cutter must sever the coil as it moves from the guide tube 55. Therefore, the action of the cutter must be positive and instantaneous.

The measuring drum 42' is provided with a gear wheel 84 (see Fig. 1) in mesh with a change gear or idler 85 which is disposed in mesh with a gear 86 secured to a shaft 87. The shaft 87 is provided with the cam member 88 having a cam surface 88' and a drop portion 88''. This cam engages a trigger member 89 journaled at 91 in a bearing 92.

One end 93 of the trigger is connected by a spring 94 to a projection 95. The spring 94 operates to hold a lug 96 at the opposite end of the trigger member normally engaged with the cam surface 88'. On the trigger member, opposite to the lug 96 is provided a lug 97 engageable with a lug 98 at the free end of a latch-piece 99, the latch-piece being pivoted at 101 on a slide plate 100. A spring 102 is provided to normally urge the latch-piece against a stop 103 so as to be in position to engage the lug 97 of the trigger 89.

The latch-piece 99 is mounted on and is movable with the plate 100 which is slideable in guides 104 and 105. It will be understood that the trigger 89 which is mounted on the bearing 92 integrally with the guides is stationary, the said guides being secured to the framework of the machine. A spring 106 is secured to a pin 107 projecting from the slide plate and a tongue 108 secured to the guide 104 normally urges the plate in the direction of the arrow "X" so that when the plate is free to move an impact member 109, adjustably secured by set screw 111 to the plate 100, will engage the end of the rocker member 75 and actuate the lever 71 to operate the cutter. The tongue 108 is stationary, being secured to the framework of the machine.

Means are provided to extend or stretch the spring 106 at which time the trigger 89 engages the latch-piece 99 and holds the slide plate in operative position so that when the trigger 89 is released the potential energy of the spring will cause the impact member 109 to actuate the lever 71. The above mentioned means for actuating the slide plate 100 so as to expand the spring may comprise mechanism in the form of a rotatable head 112 constituting what may be termed trigger setting mechanism.

The head 112 is mounted on a suitable shaft and is continuously driven by a gear wheel connected with a motor (not shown) which drives the other operating elements of the machine, as for example, the force rollers. The head 112 is provided with a projecting pin 113 disposed eccentric to the axis of rotation of the head. The pin is so arranged as to enter a notch 114 in the slide plate 100. Thus as the pin rotates with the head the slide plate will be carried in the direction of the arrow "Y" so as to expand the spring and permit the trigger member 89 to engage the latch-piece 99 and hold the plate ready for actuation.

It is necessary, however, to provide means for retracting the pin from its operative path after

it leaves the notch 114 and for holding the same retracted to permit a number of revolutions of the head 112. This is accomplished by making the pin 113 slideable in a suitable aperture in the head and providing a suitable spring (not shown) for normally urging the pin outwardly and by having a cam face 115 extending from the slide plate in the path of rotation of the pin 113 so that as the pin leaves the notch 114 it will engage a bevel face of the cam and move inwardly until an annular notch provided on the pin is engaged by one arm 118 of a bell crank member 116 pivoted on a pin in a slot in the head. An opposite arm of the bell crank is disposed in tensional relation with a spring 117 so that when an arm 118 of the bell crank member drops into the notch 114 of the plate, an arm 119 will slightly project from the slot in the head thus leaving an end of the arm 119 exposed for engagement with a contact pin which projects from the slide plate 100.

The contact pin is so positioned that when the slide plate is advanced, that is, when the spring 102 is expanded the said pin will be removed from the path of movement of the projecting end of the arm 119 but after the spring 106 is contracted and the slide plate has returned, the pin will engage the end of the arm 119 causing the bell crank member to be actuated and the arm 118 lifted from the notch in the pin 113. Whereupon, the spring will be free to act and project the pin so that the same will again enter the notch and repeat the operation of moving the slide plate 100 and expanding the spring.

It will be understood that, by reason of the present mechanism the filament wire may be moved to rotate the drum with a minimum amount of tension. As the drum rotates, the gear wheel 85 transmits motion to the cam 88 and the cam is thus rotated to actuate the trigger 89. As shown, the trigger is in position just about to drop and release the latch-piece 98. When this occurs the slide plate 100 will, under the action of the spring 106, be pulled in the direction of the arrow "X" causing an actuation of the lever 71 which results in an operation of the cutter to sever a coiled section.

The plate 100 will then be in its retracted position and the contact pin will be in position to engage the projecting end of the bell crank member to permit the pin to be projected so that upon a rotation of the head 112, the pin will enter the notch and return the slide plate 100 to an operative position. As the slide plate returns the impact member will pass the arm since the latter is free to move in one direction. As the plate 100 reaches its final returned position the latch 98 will again engage the trigger 89 to hold the cutter in operation while the cam rotates.

By reason of the present construction a section of coiled wire is severed upon each rotation of the cam 88 and inasmuch as the action occurs instantaneous, the cam continues to rotate and the driving mechanism of the machine has ample time to set the trigger before the drop portion of the cam returns for another coil cutting operation.

When the mechanism described in the foregoing is employed, the tension on the filament is reduced to a minimum which makes it possible to avoid detrimental stretching of the wire and variations due to wire slippage.

As above mentioned a coiled-coil may be made from a primary coil fed from a spool in which case the mandrelless coil-winding mechanism

may be dispensed with. It has, however, been found of great advantage from a production and quality standpoint to use the mechanism for winding a secondary coil in combination with a mandrelless coil-winding machine, as shown. 5

In operation a filament or other wire 41 is lead from a source of supply around drum 42' and between the force rollers 38 and 38'. These rollers drive the wire into a cavity die 42 from which it issues in the form of a helical primary coil 34. 10 This coil then moves through the passage 35' in the sleeve 36' and as it emerges from the end of the sleeve the separator member 49 moves between two turns of the coil and separates them. As above described the movement of the separator member and the formation of the primary coil are so timed that as each primary turn is completed the separator member operates and in accordance with the mechanism provided the operation of making the primary coil is momentarily terminated. As the separator member moves away preparatory to another separating operation, the primary coil-winding mechanism operates to bring the next turns into position for separation. The point of separation of the coils 15 thus remains the same or along a straight line parallel to the longitudinal axis of the turns and at the same circumferential point.

As the separator member operates the primary is converted into the secondary coil 50 and is 30 carried by the finger 53 which rotates at the same speed of rotation as the primary coil thus preventing the secondary coil from whipping about and serving to lead it into the tubular guide 55. The operation of making a coiled-coil may be 35 continued to make a coil of this character of an indefinite length. It is desirable, however, to provide severing means such as above described to cut the coiled-coil into definite lengths which cutting is accomplished by the timed operation 40 of the knife 60.

The present machine makes it possible to automatically perform a continuous coil-winding operation to produce a coiled-coil particularly for use as a light source for incandescent electric 45 lamps. The method may, however, be used for winding what may be termed a double helical spring for general use as for example in connection with machines or instruments where it is desirable to obtain extreme flexibility and a fixed 50 degree of tension.

Although a preferred embodiment of the invention is shown and described herein, it is to be understood that modifications may be made therein without departing from the spirit and 55 scope of the invention as set forth in the appended claims.

What is claimed is:

1. A machine of the class described comprising means for forming a primary helical coil, a 60 coil turn separator member, and means operating in timed relative movement to the coil being formed for moving said member substantially transverse to the longitudinal axis between successive turns of said primary coil to separate the 65 turns and produce a secondary helical coil.

2. A machine of the class described comprising means for forming a primary helical coil, a coil turn separator member, and means operating in timed relative movement to the coil being 70 formed for moving said member between successive turns of said primary coil to separate the turns and produce a secondary helical coil.

3. A machine of the class described comprising means for supporting a primary coil, means 75

- movable between the turns of said coil, means for causing a relative movement between said coil and said means, and means for operating said second mentioned means to engage the 5 turns of said primary coil to produce a secondary coil.
4. A machine of the class described comprising means for winding a wire into a primary helical coil, means for guiding said primary coil 10 through a predetermined path, means movable between the turns of said coil, and means for operating said movable means to space adjacent turns of the coil upon a movement of said primary coil a distance equal to the distance between the centers of adjacent turns and a guide finger to receive the primary coil after the spacing operation.
5. A machine of the class described comprising means for supporting a primary helical coil, 20 means for moving a member between the turns of said coil and means for causing a relative movement between said respective means to cause said last named means to successively separate the turns of said primary coil to form a secondary 25 coil.
6. A machine of the class described comprising means for supporting a primary helical coil, means for moving a member between the turns of said coil, means for causing a relative movement between said respective means to cause said last named means to successively separate the turns of said primary coil to form a secondary coil, and means for supporting the turns of said secondary coil.
- 30 7. A machine of the class described comprising means for supporting a primary helical coil, means for moving a member between the turns of said coil, means for causing a relative movement between said respective means to cause said last named means to successively separate the turns of said primary coil to form a secondary coil, and a finger cooperating with said second mentioned means to receive said secondary coil.
8. A machine of the class described comprising means for moving a primary helical coil 35 through a given path and a member movable transverse to the longitudinal axis of and between the successive turns of said coil for spreading the turns thereof to produce a secondary coil.
- 40 9. A machine of the class described comprising means for moving the primary helical coil through a given path, coil turn separating means and means for moving said second mentioned means transverse to the longitudinal axis of and between the successive turns of said coil to separate said turns and produce a secondary coil.
- 45 10. A machine of the class described comprising means for winding a wire into a primary helical coil, means for guiding said primary coil through a predetermined path, coil turn separator means movable between successive turns of said coil and means for moving said separator means into operative relation with said coil to space adjacent turns thereof upon a movement 50 of said coil a given distance along said path.
- 55 11. A machine of the class described comprising means for winding a wire into a primary helical coil, means for guiding said primary coil through a predetermined path, coil turn separator means movable across said path between successive turns of said coil, and means for moving said separator means to space adjacent turns of the coil upon a movement of said primary coil a distance equal to the distance between the centers of the adjacent turns of said coil.
- 60 12. A machine of the class described comprising a coil winding die, means for moving said wire into said die to form a primary coil and means movable transverse to the longitudinal axis of and between the successive turns of said coil for separating the turns thereof to produce a secondary coil.
- 65 13. A machine of the class described comprising a coil winding die, means for moving a wire into said die to form a primary helical coil and means movable transverse to the longitudinal axis of and between the successive turns of the coil for individually separating the turns of the primary coil to produce a secondary coil.
- 70 14. A machine of the class described comprising a coil winding die, means for moving a wire into said die to form a primary helical coil, means movable transverse to the longitudinal axis of and between the successive turns of said coil, said second mentioned means operating in timed relation with said first named means for individually separating the turns of said primary coil to produce a secondary coil and means for supporting said secondary coil.
- 75 15. A machine of the class described comprising means for supporting a primary coil, means movable between the turns of said coil, means for causing a relative movement between said coil and said means, means for operating said second mentioned means to engage the turns of said primary coil to produce a secondary coil and means for cutting said secondary coil into sections of predetermined lengths.
- 80 16. A machine of the class described comprising means for moving a primary helical coil through a given path, a member movable transverse to the longitudinal axis of and between the successive turns of said coil for spreading the turns thereof, means for operating said member, and coil severing means operating in timed relation with the movement of said primary coil for severing said secondary coil into predetermined lengths.
- 85 17. A machine of the class described comprising means for moving a primary helical coil through a given path, a member for spreading the turns of said coil, means for moving said member transverse to the longitudinal axis of and between the successive turns of said coil, and coil severing means operating in timed relation with the movement of said primary coil for severing said secondary coil into predetermined lengths.
- 90 18. A machine of the class described comprising means for winding a wire into a primary helical coil, means for guiding said primary coil through a predetermined path, coil turn separator means movable across said path between the successive turns of said coil, means for moving said separator means into operative relation with said coil to space adjacent turns thereof upon a movement of said coil a given distance along said path and means operating in timed relation with said first mentioned means for cutting said secondary coil into sections of predetermined lengths.
- 95 19. A machine for winding a primary helical wire into an air core secondary helix comprising means for exerting a force in the space between successive turns of the primary helix to separate the turns thereof to produce a secondary coil and means for actuating said means.
20. A machine of the class described comprising means for supporting a primary helical coil, coil turn separator means movable between suc- 75

cessive turns of said coil, means for moving said primary coil, and means for moving said separator means into operative relation with said coil to space adjacent turns thereof upon a movement 5 of said coil a given distance.

21. A machine of the class described comprising means for supporting a primary helical coil, coil turn separator means movable between successive turns of said coil, means for moving said 10 primary coil in the direction of its longitudinal axis, and means for moving said separator means to space adjacent turns of said coil upon a movement of said coil a distance equal to the distance between the centers of the adjacent turns of said 15 coil.

22. A machine of the class described comprising means for supporting a primary helical coil, and means movable transverse to the longitudinal axis of and between the successive turns of said 20 coil for separating the turns thereof to produce a secondary coil.

23. A machine of the class described comprising means for supporting a primary helical coil, and a blade movable transverse to the longitudinal 25 axis of and between the successive turns of the coil for individually separating the turns of the primary coil to produce a secondary coil.

24. A machine of the class described comprising means for causing an endwise movement of 30 a primary helical coil, means movable transverse to the longitudinal axis of and between the successive turns of said coil, said second mentioned means operating in timed relation with said first named means for individually separating the turns of said primary coil to produce a secondary coil, and means for supporting said secondary coil.

25. A machine of the class described comprising means for supporting a primary helical coil, 40 means for exerting a force in the space between successive turns of said primary coil to separate the turns thereof to produce a secondary coil.

26. A machine of the class described comprising means for supporting a primary helical coil, 45 means for exerting a force in the space between successive turns of said primary coil to separate said turns a predetermined distance to produce a secondary coil of a given pitch, and means for varying the degree of said force to separate said 50 turns a different distance to produce a secondary coil of a different pitch.

27. A machine of the class described comprising means for supporting a primary helical coil, a coil turn separator member, means for moving 55 said member successively between the turns of said coil to space said turns and produce a secondary coil of a given pitch, and means for varying the depth of movement of said member to produce a secondary coil of a different pitch.

28. A machine of the class described comprising means for supporting a primary helical coil, a blade, means for moving said blade successively 60 between the turns of said coil to space said turns and produce a secondary coil of a given pitch, and means for changing the degree of movement of said blade toward said coil to change the degree of spacing of said turns to vary the 65 pitch of said secondary coil.

29. A machine of the class described comprising a means for supporting a primary helical coil, a member movable transverse to the longitudinal axis of said coil for spreading the turns thereof a given distance to produce a secondary 5 helical coil of a given pitch, and means for changing the relative positions of said member and said primary coil to spread the turns of the primary coil a different distance to produce a secondary coil of a different pitch. 10

30. A machine of the class described comprising means for supporting a primary coil, a blade, means for actuating said blade, means for causing a timed relative movement between said blade and said coil to cause the blade to pass 15 between successive turns of the coil to separate the turns and produce a secondary coil, and means for changing the relative positions of said coil and blade to vary the depth of movement of said blade between said turns to vary the pitch 20 of said secondary coil.

31. A machine of the class described comprising means for supporting a primary coil, a blade, means for actuating said blade, means for causing a timed relative movement between said 25 blade and said coil to cause the blade to pass between successive turns of the coil to separate the turns and produce a secondary coil, and means for varying the depth of movement of said blade 30 as it passes between said turns to vary the pitch of the secondary coil.

32. A machine of the class described comprising means for supporting a primary helical coil, a rotatable blade, and means for moving said 35 blade through an arcuate path successively between the turns of said coil to space the turns and produce a secondary coil.

33. A machine of the class described comprising means for supporting a primary helical coil, a rotatable blade, means for moving said blade 40 through an arcuate path successively between the turns of said coil to space the turns and produce a secondary coil, and means for supporting the newly formed turns of said secondary coil.

34. A machine of the class described comprising means for supporting a primary helical coil, a member having a knife edge, and means for moving said member through an arcuate path successively between the turns of said coil to space the turns and produce a secondary coil. 45

35. A machine of the class described comprising means for supporting a primary helical coil, a member having a knife edge, means for moving said member through an arcuate path successively between the turns of said coil to space the turns and produce a secondary coil, and means for varying the radius of said arcuate path to vary the pitch of said secondary coil. 55

36. A machine of the class described comprising means for supporting a primary helical coil, means movable between the successive turns of said coil for separating the turns thereof to produce a secondary coil, and a supporting mandrel to receive the newly formed turns of the secondary coil. 60
